ATTORNEY.

UNITED STATES PATENT OFFICE.

AUSTIN JOHNSON, OF GRAND LEDGE, MICHIGAN.

PUMP.

1,218,086.

Specification of Letters Patent.

Patented Mar. 6, 1917.

Application filed April 3, 1916. Serial No. 88,734.

To all whom it may concern:

Be it known that I, AUSTIN JOHNSON, a citizen of the United States, residing at Grand Ledge, in the county of Eaton and 5 State of Michigan, have invented a new and useful Improvement in Pumps, of which the following is a specification.

My device relates to pumps and more particularly to that kind of pumps adapted to 10 be inserted in the casing of drilled wells, and in which a three-way device is employed for the purpose of permitting water to flow out of a spout located at or near the pump, or if desired, to cut off the water from the 15 spout and force it through pipes to a tank or any other desired locality. Its main purposes are to make a device that shall be easy to install, maintain and repair without digging a pit down to the level of the three-way 20 device, and that shall also provide proper means for the prevention of freezing and the drainage of surplus water.

I attain these purposes by the means shown in the accompanying drawings in 25 which Figure 1 is a vertical section of a pump in which my device is employed, the lower cylinder being omitted, as it may be of any ordinary construction and forms no 30 part of my present invention; Fig. 2 is a detail showing a modified construction of the drainage device.

Referring more particularly to the drawings, 1, is the outer well casing proper of the well itself in which the device is 35 mounted; 2 is a pipe connecting the upper cylinder 3 with the lower cylinder and 4 is the pump rod extending from the pump handle 5 through the upper plunger 6, to the lower plunger; these parts of the pump 40 are substantially the same as are employed in ordinary differential cylinder force pumps and may be modified in any way without departing from my invention.

My device proper consists of a pipe 7, 45 somewhat smaller in external diameter than the casing 1. This pipe is provided with a right handed screw thread at one extremity and a left hand at the other. A head 8 is adapted to screw on the lower extremity of the pipe 7 and is provided with springs 9, adapted to engage the inside of the casing 1. A second head 11 is screwed on the upper extremity of the pipe 7, and rubber packings 10 and 12 surround the 50 pipe 7, immediately in contact respectively with the heads 8 and 11. A grating 13,

wedge shaped at its two extremities, is mounted on the outside of the pipe 7 in such manner that its wedge shaped extremities will be forced by the revolution of the pipe 7 60 under the edge of the rubber packings 10 and 12 so as to expand them against the inside of the casing 1, and make a water tight joint so that the water can not pass either above or below these packings and, 65 conversely, when the pipe 7 is revolved in the opposite direction, the pressure on the packings will be released and the device may be readily withdrawn through the top of the casing 1. Water openings 14 are formed in 70 the side of the pipe 1 between the packings 10 and 12 so as to permit the water entering the pipe 7 to escape into the space between the pipe 7 and the casing 1, and thence through the opening 15 into the pipe 16 75 75 through which it is carried to any desired locality. A second pipe 17, extends from the head 11 up to and into the base of the pump; this pipe is practically an extension of the pipe 7. The upper cylinder 18 is connected 80 by a pipe 19 with the upper extremity of the pipe 17, a long screw 20 being employed for purposes of adjustment as will be more fully explained farther on. The lower extremity of the upper cylinder 18 is closed by a packing end 21, provided with passages 22, adapted to engage with upper and lower 85 seats 23 and 24 respectively. For the purpose of drainage and air circulation a pipe 25 opens into the outer casing above and below my device serving to permit the circulation of air into the casing of the well and also to drain away water from that part of the outer casing above my device. This 90 pipe is of very small diameter. In the large 95 sizes, where the outer casing is of sufficient diameter, the pipe 25 may be mounted inside the outer casing as shown in Fig. 2, but its operation is identically the same in the two 100 cases. 26 is the spout of the pump and opens out of the pipe 17 or, if desired, out of the base of the pump in such manner as to connect with the pipe 17. For the purpose of connecting the pipe 16 with the casing 1, a 105 pipe saddle 27, is secured in any desired manner to the outside of the casing 1 and prevented from leaking by packing 28. The pipe 2 is extended upward through the head 8 inside of the pipe 7 and has its upper extremity formed into a seat at the head 21.

The operation of my device is as follows: in order to mount my device in the well, it

is lowered into the outer casing and the upper extremity of the pipe 17 is attached to the body or base of the pump. The pipe 17 is then revolved in any desired manner, 5 preferably by turning the pump body. The head 8, however, is held stationary within the casing by the springs 9. The effect of this is to screw the head 8 toward the upper extremity of the pipe 7 and at the same 10 time the upper head 11 downward toward the lower extremity of the pipe 7, and thus force the wedge shaped extremities of the grating 13 under the packings 10 and 12 and expand them against the inside of the 15 casing 1 so as to entirely shut off the space inside of the casing 1 and outside of the pipe 7 between the packings so as to form a chamber between the two.

Suppose now it is desired to draw water 20 through the spout 26. The pipe 19 is turned by a head 29 or any suitable manner so as to force the head 21 downward against the lower seat 24. As the water rises into the pipe 2 from the lifting cylinder below 25 it can not enter the space 30 between the pipe 7 and the casing 1, being shut off by the head 21, and therefore rises through the 30 passages 22 in the head 21 and flows upward into the pipe 17 outside of the upper cylinder and the pipe 19 and escapes through the spout 26. If it is now desired to shut off the spout 26 and discharge the water through the pipe 16, the pipe 19 is screwed upward by the head 29 so as to bring the 35 head 21 against the upper seat; the water is thus prevented from escaping from the pipe 27 but flows outward over the upper edge of the seat 24 around the pipe 2 into the space 30, thence outward through the openings 14, the grating 13 and the saddle 27 40 into the pipe 16.

I claim as my invention and desire to secure by Letters Patent:

1. The combination in a pump provided 45 with upper and lower cylinders and adapted to be inserted in the casing of a drilled or bored well, and a pipe connecting said cylinders, of a water chamber surrounding said pipe and provided with screw threads 50 at its extremities; a collar operatively mounted on each of said threaded extremities, the lower extremity thereof being provided with means for engaging with the inner side of the well casing so as to prevent 55 revolution; packing rings mounted near the extremities of said water chamber and adapted to close the space between said chamber and said well casing; a perforated

collar surrounding said water chamber between said packing rings and provided with 60 wedging extremities adapted to force said ring into engagement with said well casing, and means for revolving said water chamber within said casing.

2. The combination in a pump provided 65 with upper and lower cylinders and adapted to be inserted in the casing of a drilled or bored well, and a pipe connecting said cylinders, of a water chamber surrounding said pipe and provided with screw threads 70 at its extremities; a collar operatively mounted on each of said threaded extremities, the lower extremity being provided with means for engaging with the inner side of the well casing so as to prevent revolution; packing rings mounted near the 75 extremities of said water chamber and adapted to close the space between said chamber and said well casing; a perforated collar surrounding said water chamber between said packing rings and provided with wedging extremities adapted to force said rings into engagement with said well casing, and a pipe connecting said water chamber with the base of said pump. 85

3. The combination in a pump provided 90 with upper and lower cylinders and adapted to be inserted in the casing of a drilled or bored well, and a pipe connecting said cylinders, of a water chamber surrounding 95 said pipe and provided with screw threads at its extremities; a collar operatively mounted on each of said threaded extremities, the lower extremity being provided with means for engaging with the inner side of the well casing so as to prevent revolution; packing rings mounted near the 100 extremities of said water chamber and adapted to close the space between said chamber and said well casing; a perforated collar surrounding said water chamber between said packing rings and provided with wedging extremities adapted to force said rings into engagement with said well casing, a pipe connecting said water chamber 105 with the base of said pump; a valve seat on the upper extremity of said water chamber and said pipe therewith; a second valve seat on the lower extremity of the pipe connecting said water chamber with 110 said pump; a valve on the lower extremity of said upper cylinder, and means for bringing said valve into engagement with either of said seats.

AUSTIN JOHNSON.
